Des. 217,315
Patented Apr. 21, 1970

217,315

POCKET COMB

Paul E. Brooks, 15347 Princeton,
Detroit, Mich. 48238

Filed Oct. 16, 1968, Ser. No. 14,018

Term of patent 14 years

Int. Cl. D28—03

U.S. Cl. D86—8

FIG. 1 is an exploded perspective view of a pocket comb showing my new design.

FIG. 2 is a plan view thereof partly assembled.

FIG. 3 is a plan view thereof fully assembled.

FIG. 4 is a side elevational view thereof.

The drawing has been shaded for transparency.

I claim:

The ornamental design for a pocket comb, substantially as shown and described.
